UNITED STATES PATENT OFFICE.

CHARLES J. SCHNAUS, OF ST. LOUIS, MISSOURI, ASSIGNOR TO EMERSON ELECTRIC MFG. CO., OF ST. LOUIS, MISSOURI.

POST-BRACKET.

1,006,598.

Specification of Letters Patent.

Patented Oct. 24, 1911.

Application filed April 15, 1911. Serial No. 621,384.

To all whom it may concern:

Be it known that I, CHARLES J. SCHNAUS, a citizen of the United States, residing at 1385 Hamilton avenue, St. Louis, Missouri, have invented a certain new and useful Improvement in Post-Brackets, of which the following is a full, clear, and exact description, such as will enable others skilled in the art to which it appertains to make and use 10 the same, reference being had to the accompanying drawings, forming part of this specification, in which—

Figure 1 is a front elevational view of my bracket in position on a post. Fig. 2 15 is a side elevational view partly in section. Fig. 3 is a detailed view of the band stirrup. Fig. 4 is a bottom plan view.

This invention relates to a new and useful improvement in post brackets, designed particularly for securing articles such as fan 20 motors, etc. to posts.

The object of this invention is to enable the bracket to be placed in position at any point on the post, the band being adjustable so as to enable the bracket to be 25 attached to posts of different sizes.

While I have shown my improved bracket for supporting motors in position, it is obvious that the bracket could be used for 30 other purposes.

In the drawings, 1 indicates a post (a bed-post being illustrated) and 2 is a casing preferably arched to straddle rings or bars on the post, allowing the bracket to be 35 mounted at any point desired and having feet 3 which are preferably faced with felt strips 4, said feet straddling the post. These feet are connected by the bridge portion of the bracket, the upper end of the bracket 40 terminating in a mount for the motor. The motor mount is in the form of a yoke 6 which is rotatably adjustable in the bracket, said yoke supporting the trunnions of the motor 7, whereby the motor may be angularly adjusted in the yoke, butterfly nuts 45 being employed to hold the motor in adjusted position. A set screw 8 may be used to cooperate with the yoke to hold the motor in rotatably adjusted positions.

9 is a stirrup which is adjustably mounted in the bracket by means of a butterfly nut 10. This stirrup cooperates with a band 11 made of canvas or other suitable flexible

material, the loops of said band passing around the bars 9^a of the stirrup.

In placing the bracket in position, one end ⁵⁵ *a* of the band 11 is wrapped around the post as shown, and then passed around one of the bars 9^a (the lower one in Fig. 4) then around the post and around the other bar 60 9^a (the upper in Fig. 4) after which the band is arranged between the end *a* and the outer member of the band and brought back around the post, its end being shown at *b*. The ends *a* and *b* are thus held in position ⁶⁵ without requiring the use of fastening devices and when the stirrup is moved outwardly from the post by means of the butterfly nut, the band is tightened and the bracket securely held in position. This ⁷⁰ manner of arranging the band with both ends free is especially desirable as the bracket can be mounted at any point of the support even though the support is a part of a continuous piece or has knobs or bars ⁷⁵ which would prevent the band being slipped into position longitudinally of the posts.

What I claim is:

1. In a device of the character described, the combination of a bracket having means ⁸⁰ for coöperating with a post, a stirrup adjustably mounted in the bracket, and a flexible binding means with which said stirrup coöperates.

2. In a device of the character described, ⁸⁵ the combination of a bracket having feet for engagement with a post, a stirrup arranged in the bracket between said feet, means for adjusting said stirrup toward and from the post and a flexible binding means ⁹⁰ coöperating with said stirrup.

3. In a device of the character described, the combination of a bracket having extremities for engagement with a post, a stirrup arranged between said extremities, ⁹⁵ means for moving said stirrup toward and from the post and a band having free ends which are threaded through the stirrup and passed around the post.

4. In a device of the character described, ¹⁰⁰ the combination of a bracket, means for securing said bracket in position on a post, said means comprising a movable member, and a band, one end of which band lies next to the post; said band passing through said ¹⁰⁵ movable member, then around said post and

again through said movable member, the opposite end of said band passing around the post and terminating between the folds of one of its loops.

- 5 5. In a device of the character described, the combination of a bracket, means for securing said bracket in position on a post; said means comprising a movable member and a band, which band is threaded through
10 said movable member and passed around the post, the end of said band being free

whereby a loop of the band is adjustable and the bracket may be secured in position on the post at any point.

In testimony whereof I hereunto affix my 15
signature in the presence of two witnesses,
this 12th day of April, 1911.

CHARLES J. SCHNAUS.
